TELEGRAPH REPEATER

Gilbert S. Vernam, Hackensack, N. J., assignor to
 Postal Telegraph-Cable Company (New York),
 New York, N. Y., a corporation of New York

Application October 27, 1937, Serial No. 171,205

13 Claims. (Cl. 178—71)

My invention relates to improvements in telegraph repeaters and particularly to single line or simplex repeaters.

One object of my invention is to design a telegraph repeater system that will operate at high speed and will accurately repeat signals, in either direction, between two single line or loop circuits.

Another object of my invention is to provide a repeater circuit with an associated switching means for cutting the repeater circuit and closing the line circuit through the associated relay winding on each side of the repeater, independent of the repeating contacts of the other relays, thus stopping the repeating of signals in both directions.

It is a further object of my invention to establish a local test circuit through the repeating contacts of both relays at the time that the repeater circuit is cut.

It is a further object of my invention to provide a repeater for single line operation in which relay locking circuits entirely separate from the line or loop circuit are provided and used with a relay having separate pairs of make and break contacts arranged so that the contacts may be adjusted to operate as make-before-break contacts.

It is a further object of my invention to provide sounder circuits combined with the separate relay locking circuits so arranged that the sounder current decreases and the locking current for each relay increases upon the closure of back contacts of the other relay.

It is a further object of my invention to provide a switching arrangement for separating the sounder and locking circuits and disabling the locking circuit of each line relay upon the cutting of the repeater circuit.

It is a still further object of my invention to provide a switching arrangement so that the repeater may be used to send and receive over separate circuits from one side thereof and still retain the locking feature which is in use for normal two line repeating of signals.

It is a still further object of my invention to provide a repeater circuit arranged to repeat both polarized signals for printer motor control or for operating call indicating signals, and make-break signals for regular communication.

Other objects and features of the invention will be presented in the particular description of my invention made with respect to the accompanying drawings, in which:

Fig. 1 discloses a schematic circuit of one form of repeater in accordance with my invention,

Fig. 2 illustrates by way of example a so-called half-set repeater connection for use with the repeater illustrated in Fig. 1.

Fig. 3 is a schematic circuit of another embodiment of a repeater in accordance with my invention, and

Fig. 4 illustrates an application of the repeater shown in Fig. 3 to a call signalling printer arrangement.

Referring more particularly to the drawings, in Fig. 1, reference numeral 11 represents a station connected by line 12 through a repeater to line 13, and the telegraph station apparatus designated generally as 14. The switches and relay contacts of the repeater circuit are shown in their normal position which they assume when the repeater is connected to a line and no signals are being transmitted. Thus, the line 12 is connected through the line relay winding 15 of line relay 16, contact 2 of switch element 22 of two position switch 3 which comprises the switch elements 17-24 inclusive, the front contact of line relay 31, contact 2 of switch element 21, to positive battery 33. Line 13 is connected through contact 2 of switch element 72 of two position switch 4, line winding 27 of line relay 31 through contact 2 of switch elements 71 and 70 of switch 4, contact 2 of switch element 20, the front contact of relay 16, contact 2 of switch element 19, contact 2 of switch element 69 of switch 4 to battery at 28. Upon the release and operation of transmitting key 11, for example, the line circuit through the line winding of relay 16 is opened and closed. Relay 16 will respond to these signals, opening and closing the line circuit through the line winding of relay 31. Upon breaking of this latter line circuit, however, a holding circuit is established for line relay 31 from ground through the holding winding 30 of line relay 31, contact 2 of switch element 17 of switch 3, the back contact of line relay 16, contact 2 of switch element 18, through resistance 36 to battery 25, so that relay 31 remains energized and the line circuit connected to transmission line 12 is not broken at the front contact of relay 31.

Similarly, when signals are being transmitted from 14, relay 31 releases, and the opening of its front contacts opens the circuit of line 12 and a holding circuit is established through the back contacts of relay 31 and contact 2 of switch element 24 to establish a holding current through the auxiliary relay winding 34 of relay 16. The contacts controlled by each of the line relays 16 and 31 are made flexible and are adjusted so

that when the relay releases, the back contacts close before the front contacts open, and when the relay operates the front contacts close before the back contacts open, so as to produce a make-before-break action and maintain the other line relay energized, so that signals may be repeated by one relay from one station to the other, without effecting the other relay. The line relays with separate contacts arranged for make-before-break operation permit the use of the repeater for repeating between two two-wire loop circuits, or received over either wire of either loop, thus permitting the repeater to be connected in series with loops of other repeaters to form a 3-way repeater as is well known in the art. This arrangement also permits the sounders to be operated in a local circuit at the repeater to avoid adding the inductance of the sounder winding in the line or loop circuit.

The operation of the sounder circuit will now be explained. With both line relays operated, as shown in Fig. 1, a circuit exists through the sounder 35, extending from battery 25 through the resistance 36, resistance 37, the winding of sounder 35 to ground. Simultaneously a parallel circuit exists from contacts 2 of switch element 18 of switch 3, resistance 38, and the auxiliary winding 30 of line relay 31 to ground. This circuit is arranged with the resistance of the various elements so chosen that the current through the relay winding 30 under these normal conditions is insufficient to operate relay 30, but the current through the sounder is sufficient to operate the sounder. A similar circuit may be traced for sounder 39 from battery 25, through resistance 40 associated with element 23 of switch 3, sounder 39 to ground, and also in parallel therewith through the auxiliary locking winding 34 of relay 16 in parallel therewith. The current through the locking winding of each of the line relays serves as a biasing current, the springs associated with the armature and relay contacts being strong enough to overcome this biasing current unless the armature is held by a current in the loop circuit. This biasing current increases the permeability of the magnetic circuit and makes the operation of the relays more sensitive.

When one of the line relays, for example relay 16, releases, its back contacts create a short circuit around resistance 38, so that the locking winding 34 of relay 31 is shunted directly across the sounder and its resistance 37. The sounder current therefore decreases, releasing the sounder, and the relay locking current increases to a value sufficient to hold relay 31 operated in spite of the fact that the line circuit is now open at the front contact of relay 16. Accordingly, the repeater will operate to repeat the signals as explained above, and simultaneously each sounder will respond to the signals repeated by the corresponding relays. Thus, these sounders may be used for monitoring the signals at the repeaters. Although, as described above, ordinary Morse telegraph keys and sounders have been shown, it is clear that the repeater circuits may be used for other types of telegraph apparatus, for example, telegraph printers or teletype printers.

It can be seen that with the repeater such as described, if trouble conditions should cause either line to go open, the other repeater will also open its circuit. The quickest method of locating the trouble is to operate a cut or breaking circuit so that each of the loops through the line relays may operate independently of the other. This will close the loop that is not in trouble and

will permit service over that part of the circuit, until the trouble is cleared.

In order to provide for such a cutting of the circuit, it is only necessary to operate switch 3 so that switch elements 17 to 24, inclusive, are each resting on contact 1. This cut circuit may also be used whenever it is desired to prevent the repeater from repeating signals from one loop to the other, as for example, to shut off a customer's station while his circuit is being lined up. It may also be used for checking the adjustment of the various relays.

The operation of the switch 3 to position 1, removes the front contacts of relay 31 from the line circuit 12 and closes the line through contact 1 of switch element 21 directly to battery 33, and similarly it removes the contacts of relay 16 from line 13 and closes line 13 through contact 1 of switch element 19 to battery 28, permitting communication over these independent loop circuits without repeating signals from either loop to the other. At the same time the shut releasing circuits of sounders 35 and 39 are closed through the relay back contacts directly to ground, and the biasing circuits through the auxiliary windings of relays 16 and 31 are separately energized through contact 1 of switch elements 23 and 18, respectively. Accordingly, the signals from 11 and 14 may be independently received at the relay station over line relays 16 and 31 operating substantially in the same way as previously described to energize sounders 35 and 39. Simultaneously a test circuit is produced from battery 25 through test jack 41, front contact of relay 16, contact 1 of switch element 20, front contact of relay 31 and contact 1 of switch element 22 to ground, permitting a test to be made of the relay contacts to determine any faults that may exist therein. By inserting a plug connected to a milliammeter in jack 41 the output signals of either relay may be tested, and the relays may be conveniently adjusted to repeat unbiased signals.

It is sometimes desirable to connect a single line repeater to the sending and receiving legs of a duplex terminal set so that signals being transmitted in either direction over a duplex line may be transmitted or received through the repeater to or from a single wire line or a single loop circuit. When used in such a connection, the repeater is termed a half-set repeater, and it provides means for furnishing single or "half-duplex" operation over a duplexed line. In accordance with my invention provisions are made for switching the connections of the repeater illustrated in Fig. 1 to operate as a half-set. To convert the repeater illustrated in Fig. 1 for half-duplex operation, switch 4 is moved to the left position illustrated in Fig. 1, whereby switch 4 is arranged so that its various switching elements are on the number 1 contacts. Thus, connections 50, 51, 52 and 53 of Fig. 1.

Fig. 2 illustrates the connection of these wires to the sending and receiving legs of a duplex terminal set circuit for operation with the repeater in a half-duplex arrangement. With this arrangement, signals from 11 are transmitted through the winding of relay 16 in the same manner as previously described. However, the sending device 14 and line 13 are disconnected from the line winding of relay 31 by the movement of the switch element 72 from contact 2 to contact 1, and the circuit to the line winding 27 of relay 31 now extends from contact 101 of duplex line relay 105 (Fig. 2), through "receiving leg" con-

ductor 53, contact 1 of switch element 72 (Fig. 1), through the rheostat, line winding 27 of relay 31, contact 1 of switch element 71, and conductor 52 to ground at 102. Thus, relay 31 serves as a receiving relay for receiving signals incoming over line 104 of Fig. 2, which is the terminal of a duplex line. Signals incoming over line 104 operate polarized relay 105 to make and break the contacts 101 in accordance with the signals. These signals incoming over line 53 through relay 31 serve to make and break its front contacts, thus repeating the signals through the repeater to receiver 11 and simultaneously operating the receiving sounder 39 at the repeater for monitoring purposes.

For transmission of signals from 11 to the duplex line, the battery connection of the front contacts of relay 16 is broken at contact 2 of switch element 69 and disconnected through contact 1, "sending leg", conductor 50, and the winding of pole changer relay 106 to positive battery at 107. This circuit then extends from battery 107 through the circuit just named, contact 2 of switch element 19, front contacts of relay 16, contact 2 of switch element 20, contact 1 of switch element 70 and conductor 51 to ground at 108. Associated with relay 106 are two contacts, front contact F being associated with a negative battery and back contact B being associated with a positive battery. Contact tongue 109 is connected through a suitable conductor 110 and inductance 111 to the midpoint of the relay winding of relay 105.

Accordingly, signals transmitted from 11 serve to make and break the sending leg circuit at the front contact of relay 16, thus causing alternate energizing and deenergizing of relay 106 and operating contact tongue 109 to alternately apply positive and negative signal impulses to the line 104 over the winding of relay 105. Since these signals are applied at the midpoint of relay winding 105, in accordance with the well known method of duplex operation, they will have equal and opposite effects upon the two windings of the polar relay 105 and accordingly will not affect the contact 101. Since the sounder circuit and the relay holding circuit are identical with those above described, a repetition of the operation of these circuits is not considered necessary at this point.

Fig. 3 discloses another form of repeater in accordance with my invention. In this figure, a conventional printer circuit is illustrated as the main office printer at 330 enclosed in broken lines, arranged to be connected through a jack of a switchboard 302, within the broken line block and through line 303, to the terminal 304 of the repeater. Incoming signals from the printer are applied through a line jack and resistor, line 303, contact 2 of switch element 304, front contacts of relay 316, contact 2 of switch element 306, the upper winding 317 of relay 318, contact 1 of switch element 321, the lower winding 323 of relay 318, contact 1 of switch element 320, through resistance 324 to negative battery.

Another printer station 330, shown at the right of the figure enclosed by broken lines is connected over line 331 to terminal 332 of the repeater, and a circuit is established through contact 2 of switch element 308, front contact of relay 318, contact 2 of switch element 307, the winding 333 of relay 316, back contact associated with spring 335 of relay 334, resistance 336 to positive supply at 326. Thus incoming signals from the main station operate relay 318 to make

and break the front contacts of relay 318 and transmit the signals through to printer station 330. Likewise, printer signals from printer 330 operate relay 316 to make and break its front contact and transmit signals to printer 301.

When the front contact of relay 318 opens, the back contact closes, thus establishing a holding circuit for relay 316 from positive battery at 326, through the winding of relay 316, contact 2 of switch element 308, the back contact of relay 318 and resistance 339 to ground at 340, preventing the front contact of relay 316 from opening.

Similarly, when signals transmitted from 330 operate to open the front contact of relay 316, the back contact of this relay closes, establishing a circuit from negative battery at 326 through contact 1 of the switch element 320, winding 323 of relay 318, contact 1 of switch element 321, winding 317 of relay 318, contact 2 of switch element 308, back contact of relay 316, conductor 341, contact 1 of switch element 319, conductor 342, resistance 343, to ground at 340, thus establishing a holding circuit for relay 318, so that it will not open its contacts. The contact springs of relays 316 and 318 are made flexible and adjusted to make-before-break so that the holding circuits for the respective relays will be maintained.

Contact switch elements 304 to 310, inclusive, are elements of a single switch for two-position operation indicated generally at 345 and contact elements 319 to 321 are elements of the three-position switch indicated generally at 346.

With switch 345 in the number two position as shown, and switch 346 in its number one position as shown, the repeater operates as a straight, through repeater, similar to that illustrated in Fig. 1. By throwing a switch 345 to the right to establish circuits through the number one contacts, a cut circuit may be established for this repeater so that signals incoming thereover will not be repeated to the other line. With the switch thrown to this position signals incoming from 301 traverse the circuit from terminal 304 through contact 1 of switch element 305, winding 317 of relay 318, contact 1 of switch element 321, lower winding 323 of relay 318, contact 1 of switch element 320 and resistance 324 to negative battery at 326. It can thus be seen that the circuit no longer traverses the contacts controlled by relay 316.

Similarly, signals incoming from printer 330 traverse line 331, contact 1 of switch element 308, the winding 333 of relay 316 and the contact of relay 334 to positive battery at 326, as previously traced. Simultaneously a test circuit is established extending from positive battery at 326, test jack 347, contact 1 of switch element 304, front contact of relay 316, contact 1 of switch element 306, contact 1 of switch element 307, front contact of relay 318, contact 1 of switch element 309, resistance 339 to ground at 340. This produces a test circuit, enabling the testing and adjustment of the separate contacts of the two repeater relays, similar to that described in connection with Fig. 1.

In Fig. 3, a motor control circuit for controlling the motor at station 330 from the main office station 301 is shown. This motor control circuit is established by turning three-position switch 346 to its number three position. The removal of switch element 321 from the number one contact, removes a short circuit which previously existed around polar relay 348, and connects this polar relay effectively in series between

windings 317 and 323 of relay 318. When the circuit is idle, the plug is removed from the jack at the main office and negative current supplied from the main office switchboard, through the winding of relay 361, inner contact of the jack, over the line 303 serves to maintain polar relay 348 operated, thus closing the contact 350.

A circuit extending from ground through conductor 353, the winding of switch relay 334, conductor 354, contact 3 of switch element 322, contact 2 of switch element 310, conductor 355, contact 350, resistance 324, to negative current supply at 326 serves to energize relay 334 thus closing its front contacts 335, 336 and 337. From the repeater a circuit to station 330 may be traced, from negative battery at 326, through resistance 324, front contact of relay 334, contact arm 335, winding 323 of relay 316, through the circuit previously traced to line 331, through polarized relay 363, motor control relay 365, front contact of relay 363 to ground. Relay 365 being energized operates to hold the motor circuit open.

In order to establish communication by calling from station 330, break key 360 is operated, thus breaking the line circuit and closing it again. This will release and re-operate relay 316 but relay 318 and polar relay 348 will remain energized. The contacts of relay 316 will open and close again releasing relay 361 at the main office switchboard, and lighting the lamp 362. When released a contact of relay 361 short circuits its operating winding, so that relay 361 remains released after the line closes. When the cord associated with printer 301 at the main office is plugged in to the line jack, positive current is supplied to line 303 and relay 348 will be released, also releasing switch relay 334. Insertion of the plug into the jack closes a circuit through a separate winding on relay 361, restoring its contacts to normal and also completes a circuit through control relay 390, applying positive battery to printer 301. Release of switch relay 334 connects positive battery to line 331 from 326 through resistance 323, back contact of 335, the winding of relay 316, back through the repeater to line 331 as previously traced, and also connects the positive battery to the locking relay circuit of relay 318 from terminal 326, through the back contact of 337, contact 3 of switch element 319, back contact of relay 316, contact 2 of switch element 305 to the relay winding of 317 through polar winding of 348, winding 323, as previously traced. This positive current on line 331 operates through the polar relay 363 to release the contacts 364, short circuiting motor relay 365, and closing the motor circuit to start the printer motor. A more complete description of the motor operating arrangement may be found in Patent No. 1,773,952, of A. F. Connery, issued August 26, 1930.

Relays 348 and 334 remain released while the printer signals are being transmitted through the repeater in either direction. The operation of the repeater in repeating these printer signals is the same as previously described. A resistance 366 is shunted across the winding of relay 318 from ground at 340, through resistance 366, contact 3 of switch element 321 to the upper terminal of winding 323, to reduce the inductive discharge from this relay winding when the circuit is opened at the main office 361. Without this shunt circuit the discharge may be sufficient to operate polar relay 348 during the transmission of the signals. When the communication is completed, the plug may be removed at station 301,

reconnecting negative battery from 302 to the line, thus stopping the station motor by the operation of polar relay 363 and restoring the line to normal.

Although the motor control circuit has been described with a source of both negative and positive direct current supplied at the repeater a single repeater may be installed with a single rectifier or motor generator arranged to supply both current polarities at the repeater by reversal of the rectifier or generator. In such a case the rectifier or generator should not be grounded but both terminals should be connected to the repeater terminals at 326 in Fig. 3. Terminal 367 should then be connected to ground. The connection between ground and wire 353 should be removed and a connection made from 353 to terminal 369. Then when either terminal of the rectifier or generator is connected through contact spring 335 of relay 334 of the repeater to the station line, the other terminal will be grounded through spring 336 of switching relay 334.

It is sometimes desired to provide a calling system to be operated from the main station for calling several subscribers' printer sets so that the desired called station may be connected to the line. In accordance with my invention such a system is indicated generally at 401, connected through push button switch or break key 402, line 403, polar relay 404 at printer set 405, line 406, repeater 407, line 409, polar relay 408, station printer set 410, and a suitable resistance 411, to a negative battery at 412.

The repeater station indicated at 407 in Fig. 4 may be a repeater such as that illustrated in Fig. 3, with the switch 346 to the left or No. 3 position or with switch 346 moved to its central or number 2 position. If the line sections are short enough so that they may be operated to ground at one end, that is if the first line section may be operated from battery at the main office to ground at the repeater, and the second section operated from battery at the repeater to ground at the terminal station, then the repeater of Fig. 3 may be used with switch 346 in the No. 3 position, as described above, and the polar signals transmitted over the line used to operate call bells or other signal apparatus to indicate the desired station to be connected. With this arrangement a printer circuit such as shown in Fig. 4 is used. The break-key 402 at station 401 may be operated successively to transmit the code signals indicative of the desired station, and the relay 365 may be arranged to operate a bell instead of closing the motor circuit.

However, the operation of the circuit of Fig. 4 with switch 346 in the No. 2 position is more useful in cases where the lines are long. Negative battery is connected to line 406 from negative terminal at 326 through resistance 371, contact 2 of switch element 320, winding 323 of relay 318, winding of polar relay 348, winding 317 of relay 318, through the circuit previously traced to terminal 304 and to line 406. The resistance 371 and grounded resistance 343 which is connected to relay 318 through contact 2 of switch element 320 form a potentiometer, which operate to reduce the negative voltage supplied, below that of the negative battery 430 at the main office.

In the normal condition current from positive battery is connected to the line at station 401 and flows through relay 348 in a direction to normally maintain its contact 350 open. Interrupting this circuit to call the main station 401 or to transmit printer signals will have no effect, since the relay

biasing spring tends to hold the relay contact 350 open. When the push button 402 at the main office is operated a reverse current is impressed on the line from negative battery 430, which current has a reduced strength due to the negative supply which is impressed on the line at the repeater. This reduced current is sufficient to operate relay 404 or any other polar relays between the main central station and the relay station, 10 operating the call bell at any of these stations. Relay 318 will release as this weak current in its upper winding 317 opposes the current through its lower winding 323 and resistance 343, but the reversed current through the line will simultaneously operate relay 348 closing contact 350. 15 Opening of the front contact of relay 318 will break the positive line supply on line 409 which formerly was supplied from the positive terminal of 326 and will impress on the line negative polarity from the negative terminal of 326 through resistance 324, contact 350, conductor 355, contact 2 of switch element 310, contact 2 of switch element 322 to terminal 332.

This will impress a negative current on line 25 409 operating the polar relays 408 and ringing the bell at station 410, and any other stations which may be interposed in the line. When the push button 402 is released at the main office, positive battery is again connected to the line releasing relay 348 and reoperating the repeater relay 318. These operations may be repeated every 30 time the push button is depressed, thus ringing the bell as many times as desired. Any station may be called by assigning a particular number 35 or code of the call bells thereto so that when the proper signal is received the printer at that station may be connected to the line.

Instead of repeating the current reversal to operate signal bells at other stations, it may be desired in some cases to use the single stroke bell to call the repeater station only. This may be done by opening line 355, Fig. 3, and connecting a signal bell from the part of conductor 355 connected with contact 350 to ground through a suitable resistance. Relay 348 will then respond to current reversal in the main line, but will operate the local signal bell instead of repeating the reversals over the other line.

The cut switch 345 may be used as well with the motor control and call bell circuit as with the straight repeater circuit first described. It should be noted that when switch 345 is in the number 1 or cut position the polar relay control circuit of 348 is broken at contact 2 of switch element 310, and the switching relay circuit of 355 switching relay 334 will be broken likewise at the same contact so that these relays will be inoperative at these times. With this arrangement the line relays 316 and 318 will operate only to transmit signals through the test circuit and will not in any way affect the transfer of signals between stations on each of the now separate line sections.

While I have described my invention with relation to several specific embodiments thereof, it should be understood that these illustrations are merely intended to describe the principles of operation of my invention and not as a definition of the scope thereof. Any changes and substitution of parts may be made therein within the scope of the appended claims which thereto define my invention.

What is claimed is:

1. A repeater system comprising, a first transmission line, a second transmission line, a nor-

mally energized relay operatively connected in each transmission line, contact means in each line controlled by the relay in the other line, each of said relays being responsive to signal current fluctuations in the transmission line associated therewith to open and close contacts of said contact means in said other line for repeating signals thereto, means operative upon opening of said contacts in either of said lines for maintaining the relay in the opened line energized 10 during the signal current fluctuations, and switching means for disconnecting said contact means from both of said lines and completing the energizing circuit of said relays independent of said contacts for stopping the repeating of 15 said signals from one line to the other, said switching means establishing a local circuit through both of said contact means upon disconnection of said contact means from said lines.

2. A repeater system according to claim 1, in 20 which said means for maintaining said relays energized comprises a local circuit connected to a winding on each of said line relays, and said contact means in each of said lines comprises a pair of make-before-break contact switches, one 25 of the switches of each said pair being connected in the transmission line and the other switch of said pair being connected to close said local circuit upon opening of said line switch contact.

3. A repeater system according to claim 1, in 30 which said means for maintaining said relays energized comprises a local circuit connected to a separate winding on each of said line relays, and further comprising a sounder circuit connected in shunt with each of said separate windings and 35 means for operating said sounder upon operation of said repeating contacts.

4. A repeater system according to claim 1, in 40 which said means operative upon opening of the contacts for maintaining the relays in the lines energized, comprises a local energizing circuit connected to the main relay winding of said 45 relays.

5. A telegraph system comprising a main office telegraph signalling station connected to a first line section, a repeater connected to said first line section for repeating signal impulses and telegraph signalling stations connected to the output of said repeater through a second line section, means at said main office for supplying a normal potential to said first line section, a polar neutral line relay in said first line section at 50 said repeater normally energized by said normal potential supply, a polar relay in said first line section at said repeater normally unoperated by 55 said normal potential supply, means in said second line section at said repeater responsive to signal impulses for repeating signals from said first line section to said second line section, polar relays in said second line section at each of said 60 telegraph stations, unresponsive to normal repeated signal impulses, means for maintaining a normal potential on said second line section, means at said main office station for introducing a current of polarity opposite to said normal 65 polarity upon said first line section for operating said first named polar relay, means in said second line section responsive to operation of said first named polar relay for introducing a current of polarity opposite to said normally 70 maintained potential on said second line section for energizing said other polar relays, and operating means at said telegraph stations responsive to energization of said polar relays.

6. A telegraph system according to claim 5 in 75

which said polar relays in said second line section control call signal indicating means.

7. A telegraph repeater comprising a first line section, contact means in said line section, a first polar neutral line relay responsive to normal make and break line signals, line signals, having a line winding connected to said first line section, a polar relay, responsive to polar call signals, having a winding connected to said first line section, a second line section, contacts means in said second line section controlled by said first polar neutral line relay to repeat said make and break line signals, a second line relay responsive to normal line signals, having a line winding connected to said second line section, said second line relay controlling repeater contacts in said first line section, and a local circuit controlled by said polar relay operative to supply potential of the polarity of said polar signals to said second line section, whereby said repeater operates to repeat signals by the operation of said line relays and to translate polar signals by the operation of said polar relay.

8. A telegraph repeater according to claim 7, further comprising back contacts operative with said contact means in said first and second line sections, and another local circuit connecting line relays and said back contacts for maintaining said line relays operated upon the opening of the contacts in the line section connected thereto.

9. A telegraph repeater according to claim 7, in which said local circuit is connected to said second line section, whereby said polar call signals serve to repeat said call signals to said second line section.

10. A telegraph repeater according to claim 7, further comprising switching means for disconnecting said line contact means from their respective line sections, and completing another local circuit through said contacts responsive to signals on said line section.

11. A telegraph repeater according to claim 7, further comprising switching means for rendering said polar relay effective or ineffective for operation by polar signals incoming over said first line section.

12. A telegraph repeater system comprising a first line section, a line relay in said first line section, a second line section, a line relay in said second line section, front contact means in each of said line sections controlled by the relays in the other line section, back contact means controlled by said line relays for closing a holding circuit for the corresponding line relay upon opening of said front contact, a polar relay connected to said first line section, and switching means movable to alternative switching positions, for rendering said polar relay ineffective in one position, connecting said polar relay to control a call signal indicator in a second position, and connecting said polar relay to control telegraph motors in a third position.

13. A telegraph repeater according to claim 12, further comprising a local test circuit and a cut switching means adjustable to two positions, said cut switching means in one position connecting said front contact means in said line sections and in the other position disconnecting said front contacts from said line sections and closing said local test circuit through said front contacts.
